UNITED STATES PATENT OFFICE.

HENRY TIDEMAN, OF MENOMINEE, MICHIGAN.

TELEPHONE-RINGER.

No. 901,215.

Specification of Letters Patent.

Patented Oct. 13, 1908.

Application filed July 6, 1907. Serial No. 382,430.

To all whom it may concern:

Be it known that I, HENRY TIDEMAN, a citizen of the United States of America, and a resident of Menominee, county of Menominee, and State of Michigan, have invented 5 a new and useful Improvement in Telephone-Ringers, of which the following is a specification.

My invention pertains to improvements in 10 the mechanical structure of telephone signaling devices and particularly to telephone ringers.

My invention has as its object the provision of improved type of telephone ringer 15 with improved self-locking adjusting means for the armature and cores thereof and with improved core terminals whereby the likelihood of accidental cross of the conductors with the ringer frame is much reduced.

20 I provide the adjustment means by putting a magnetic screw threaded head upon the cores of the ringer, the screw threads of the head being provided with auxiliary tension means whereby they grip tightly the 25 external threads of the core. The reduction of liability to accidental crosses of the conductor with the frame is provided for by false heads or shields placed over the core heads at the ends where the conductors are 30 brought out.

In the drawings Figure 1 shows front 35 view of the ringer; Fig. 2 shows side view; Fig. 3 shows a central section in the same direction of view as Fig. 1; Fig. 4 shows perspective of the screw threaded magnetic core head; and Fig. 5 shows the spring element 40 whereby the core head of Fig. 4 is given an elastic tension.

In Fig. 1, 10 is a permanent magnet, 11 is 45 a magnetic yoke to which is attached permanent magnet 10 and the cores and spools 12 12. The yoke 11 is extended beyond the length necessary to mount the magnet and cores, and in its extensions is formed to 50 provide contact surfaces for the inner surface of the bell box, the ends being perforated whereby a screw may be passed through yoke 11 to mount the complete device upon the inner surface of the bell box, the taper 55 13 projecting through the wall of the bell box.

The cores 14 are threaded externally at the end 14'. The non-magnetic yoke 15 is perforated at its ends to pass over the core ends 55 14', and carries in its median portion ears

and trunnions for the armature 16. Lock nuts or lock rings 14" engage the outer threads of the core ends 14'.

The core ends 14' are drilled and threaded internally to receive the magnetic core heads 60 17. Detail of the core head 17 is shown in perspective in Fig. 4; it is a hexagonally headed screw drilled axially at 17' and slotted at 17". As this is desirably of the softest quality of iron, it has little or no 65 elasticity, and I provide for the elasticity of the two split halves of the screw by inserting in the opening at 17' the cylinder 18 which is split at 18' through a portion of its length. The split plug 18 is essentially of spring 70 metal but may be magnetic or non-magnetic, brass answering the purpose. The split plug 18 is driven into the split screw 17, spreading the halves of the screw 17; screw 17 is then compressed and screwed into the core end 75 14', the friction of screw threads being great on account of the spring tension of the split cylinder 18.

At 19 is shown the spool head of the spool 80 12, and at 20 is shown the false head or insulating washer in a drive fit over the core 14. The conductors 21 are twisted together and clipped short and by reason of being held away from the yoke 11 and other structural parts by the guard heads 20, a cross 85 with the frame is almost impossible. The conductors 22 are also brought out between the heads 19 and 20, and the likelihood of cross with adjacent portions of the frame is reduced by the presence of the guard head 20. 90

The assembly of the device in manufacture is as follows: Upon the yoke 11 are mounted the spools 12; the connection of the conductors at 21 then is made; the yoke 15 is placed over the free ends of the cores 14; the 95 lock washers or lock nuts 14" are screwed down firmly to clamp the yoke 15 against the core heads 23, thus locking the yoke 15 firmly. The magnetic core heads 17 then are placed in position and screwed down 100 closely. The armature 16 is placed in the trunnions and the trunnions are adjusted. The permanent magnet 10 then is mounted and the device is complete, ready for adjustment. The adjustment is made by unscrewing the core heads 17 until by their approach to the armature the proper distances are attained when the adjustment is complete, as the friction of the threads of the part 17 is sufficient locking means. The non-magnetic 110

contact points 24 provide against sticking of the armature to the magnetic core heads. After the ringer and gongs have been mounted upon the bell box, adjustment of the tapper 13 to the gongs is sometimes required. This may be made by bending the rod of the tapper 13, by moving the gongs respectively, or, in the device of my invention herein shown, may be made by relative adjustment 10 of the core heads 17.

Having thus described my invention, what I claim as new and desire to secure by United States Letters Patent is:

1. In a telephone ringer, a core drilled and threaded internally at its armature end, a core head for said core having a shank screw-threaded to engage the internal threads of said core, the shank of said core head being axially drilled and longitudinally slotted, 15 and means located within said shank for separating said shank whereby an increased friction of the screw threads of said shank

with the internal screw threads of said core may be attained, substantially as described.

2. In a telephone ringer, a core drilled and 25 threaded internally at its armature end, a core head for said core having a shank screw-threaded to engage the internal threads of said core, the shank of said core head being axially drilled and longitudinally slotted, 30 and a cylindrical plug of spring metal split through a portion of its length and placed within the recess in said shank, whereby said shank may be spread under elastic tension to engage frictionally the threaded walls of 35 said core end, substantially as described.

Signed by me at Menominee, county of Menominee and State of Michigan, in the presence of two witnesses.

HENRY TIDEMAN.
